THERMOMETRIC METHOD AND APPARATUS
FOR DETERMINING THE AMOUNT OF IMPREGNITE IN CLOTHWarren C. Johnson and Philip Wehner, Chicago,
Ill., assignors to the United States of America
as represented by the Secretary of the Navy

Application May 22, 1945, Serial No. 595,144

4 Claims. (Cl. 23—230)

1

This invention relates to a method of and apparatus for determining the amount of impregnite in impregnated cloth. This method is based upon a determination of the heat or other effects produced when the impregnated cloth comes in contact with a reducing agent.

This method has been developed to provide a practical and rapid evaluation, for shipboard and field use, of the protective capacity of impregnated clothing against vesicants. It is not intended to serve as a means for the quantitative determination of the amount of impregnite in cloth, but to provide a very satisfactory indication of whether a given cloth contains no impregnite, a moderate amount, or is fully impregnated. In other words, it is to be used for determining whether impregnated cloths offer no protection, moderate protection, or full protection against vesicants.

The term "impregnite" includes those compounds which are capable of reacting with vesicants and rendering them non-vesicant. In general, the term includes water-insoluble oxidizing agents containing nitrogen and chlorine in —N—CL groups, such as chloramides and chloro-ureas. In the reaction of impregnite with vesicants, the vesicants act as reducing agents, and for the purpose of determining the amount of impregnite in impregnated cloth, either the vesicants themselves or other reducing agents which react in a similar manner may be utilized. These other reducing agents may be termed "simulants" or "mustard simulants", and include such compounds as phenyl hydrazine, hydrogen sulfide, thioxane (1,4-oxthiane), dithiane (1,4-diethyl-3,5-enedisulfide), aniline, triethylamine, and piperidine.

The determination is based upon the fact that an approximately linear relationship exists in the amount of heat or other effects liberated in the reaction between an impregnite and a reducing agent. When a certain amount of a chemical reagent, such as phenylhydrazine, is applied to a prescribed area of fabric, say one inch in diameter, containing impregnite, there is a reaction which evolves heat or other effects. The greater the content of impregnite in a given quantity of cloth the greater the amount of heat or other effects evolved.

The determination of the amount of heat evolved in the reaction is obtained by the use of a thermopile in close proximity to the reacting cloth. The amount of heat liberated in the reaction is indicated by the deflection of a suitable galvanometer movement. The galvanometer de-

2

flection is approximately proportional to the amount of impregnite in the cloth. It is necessary to calibrate the galvanometer movement with an identical cloth containing known amounts of impregnite. It appears that the heat effect is independent of the type of impregnite contained in the cloth. The accuracy of the determination by this method is found to be within 10 to 15 percent of the impregnite content determined by direct quantitative analysis.

It is evident that in order to obtain the maximum heat effect from a given area of cloth containing the impregnite, it is essential to overwhelm the impregnite with a reducing agent, so to speak, in order to obtain the heat of the reaction in as short a period of time as possible. This can be done by using a liquid reducing agent, or a solution of a solid reducing agent, which will penetrate the cloth and cause immediate reaction with the impregnite. Such a reducing agent, however, should not be too volatile, since a cooling effect would then be obtained due to the heat of evaporation.

The measurements are accomplished by means of an apparatus designed for use with a specified amount of a reagent on a definite area of cloth, separated by a fixed distance from a thermopile.

The principal object of this invention is to provide a method of determining the amount of impregnite in cloth by applying phenylhydrazine to an impregnated cloth and associating the heat liberated therefrom with a thermopile.

Another object of this invention is to provide a method of determining the amount of impregnite by subjecting impregnated materials to the influence of a reducing agent and associating the effects thereof with indicating means.

A still further object of this invention is to provide an instrument for measuring the amount of impregnite in cloth.

The invention will now be described with reference to the accompanying drawing, in which:

The figure is a half sectional drawing of the device electrically connected to a galvanometer.

Referring to the drawing, numeral 1 indicates a tubular glass housing in which is mounted a thermopile 2 embedded in a core 3 of plaster of paris. Said core is molded in said tube approximately $\frac{1}{8}$ inch from the top end of said tube so as to provide a large lower chamber 5 and a small upper chamber 4. The hot junctions 6 of said thermopile 2 protrude through the top of plaster core 3, and the cold junctions 7 protrude through the bottom of said plaster core 3, so that said exposed thermojunctions can be freely subjected to

a thermal environment. As a consequence of such mounting, the hot junctions are approximately $\frac{1}{8}$ inch from the top end of tube 1. Thermopile terminals 7 and 8 are connected to galvanometer 9 terminals 10 and 11, respectively. Said galvanometer is calibrated with cloth identical to that to be tested, and containing known amounts of impregnite. Small holes 19 and 14 are provided in the wall of tube 1 to allow the passage of conductors 15 and 16 that connect the thermopile 2 with the galvanometer 9. Lower chamber 5 which contains the cold junctions 17 is sealed off with a glass plate 18.

In making an analysis, a single thickness of the cloth 12 to be tested is stretched across the upper open end of the glass tube 1 and held in place by a glass ring 13 which fits around the periphery of said tube. Thus the cloth is firmly held between the ring 13 and the periphery of the glass housing. After allowing about 30 seconds for the galvanometer 9 to return to the zero point and to become steady, two drops of a mustard simulant, for example, phenylhydrazine, is then placed at the center of the cloth sample within the ring. Two drops, approximately 0.1 cc., of the liquid is used in each test, but it should be stated that the amount of the liquid simulant is not particularly critical, since if only one drop is used, the deflection is found to be only 10% less, and three drops increases the deflection only slightly. After the liquid simulant has been administered, the galvanometer needle moves slowly over a period of about ten seconds to a maximum value, where it remains for a few seconds, and then slowly returns to its former position. After the maximum deflection has been read, the cloth is removed and the upper chamber 4 containing the hot junctions is allowed to stand for two to three minutes to permit diffusion of the simulant vapors out of said chamber. It is found that this amount of time is required before the galvanometer needle returns to its initial position. The total time required for carrying out such a test is about four minutes, though this may be reduced by flushing the chamber 4 with an air stream. It is necessary to allow the upper chamber 4 to become free from simulant vapors before another test is carried out, otherwise those vapors will react with a fresh piece of cloth and thereby produce erroneous results. For convenience, the zero point of the galvanometer is usually taken as a few millimeters from the extreme left-hand side of the scale. It is found necessary, after the cloth is inserted, to wait about one-half minute for the galvanometer needle to reach the selected zero point, since a heat effect is produced merely by the process of inserting the cloth into its fixed position.

In the testing of cloth, mustard vesicant either in the liquid or vapor form may be used directly, but for shipboard use or for field use it is evident that it would be more desirable to use a substance which reacts with the impregnite in a manner similar to that of mustard vesicant, but which does not have the objectionable properties which mustard vesicant possesses. In addition, the rate of the reaction between mustard vesicant and an impregnite is not as high as one would like for a rapid test.

Gas, such as hydrogen sulfide and sulfur dioxide can be used as the mustard simulant. Whereas fairly reproducible results can be obtained with the gases, they nevertheless possess several disadvantages. In the first place, the rate of the reaction between the gas and the im-

pregnate is low and in addition, the heat effects are small. Another objectionable feature is the odor and toxicity of these two gases.

5 A number of liquid simulants can be used, such as triethylamine, piperidine, dimethyl sulfide, thioxane, aniline, phenylhydrazine, dithiane dissolved in acetylene tetrachloride, p-phenylene diamine dissolved in acetylene tetrachloride, and solutions of these same substances in aniline.

10 In the case of the triethylamine, the heat effect is large, but there is also a marked cooling effect due to the rapid evaporation of the solvent. Piperidine behaves in a manner quite similar to that of triethylamine. Dimethyl sulfide is extremely unpleasant to work with, and in addition, possesses the disadvantages of triethylamine. Thioxane also has a disagreeable odor and the heat effect produced is only about half that obtained with phenylhydrazine. In the case 15 of the solutions the heat effects are too small in each instance. Aniline appears to be about as satisfactory as phenylhydrazine; the heat effect obtained is about the same and the rate of evaporation is not too great. Of all the simulants tested, phenylhydrazine appears to be the 20 most satisfactory.

25 It is understood that reducing agents can be used that liberate effects other than heat, so that responsive means such as a photo electric cell could be used in lieu of a thermopile to indicate measurements of impregnate content through means of the light effect emitted from the reaction.

30 It is also understood that the cooling effect 35 of a reaction could be utilized as well as the heat effect of a reaction. In this event, the galvanometer movement could be arranged for a swing clearance to the left instead of to the right as hereinbefore provided.

40 Reducing agents in the form of solids, liquids, or gases can be used with this method; however, those chemicals are preferred that have a high rate of reaction with the impregnate.

What we claim is:

45 1. In a method of determining the amount of impregnate in cloth, the steps of measuring a specific area of impregnated cloth, placing said area of impregnated cloth a fixed cooperative distance from the hot junctions of a thermopile connected to a galvanometer, applying a specific quantity of at least one reducing agent selected from the group consisting of phenylhydrazine and aniline to said impregnated cloth, reading said galvanometer, and calibrating said thermopile 50 and said galvanometer with an identical cloth and area containing known amounts of impregnate and said specific quantity of said reducing agent.

60 2. In a method of determining the amount of impregnate in cloth, the steps of placing impregnated cloth a cooperative distance from thermal responsive means connected to a galvanometer, applying to said cloth a known quantity of a reducing agent which liberates heat in reaction 65 with impregnate, reading said galvanometer, and calibrating said thermal responsive means and said galvanometer with an identical cloth containing a known amount of impregnate.

65 3. The method of measuring the amount of 70 impregnate in cloth comprising the steps of placing impregnated cloth a cooperative distance from thermal responsive means calibrated with an identical cloth under identical conditions containing known amounts of impregnate, applying 75 an associated known quantity of a reducing agent

which liberates heat in reaction with impregnite, and measuring the amount of heat liberated, whereby the standard and unknown may be compared.

4. In a device for measuring the impregnation of cloth with impregnite, an upright container having an open upper end, a thermopile having a hot function end and a cold function end, insulating means supporting said thermopile within said container with the hot function end thereof adjacent the open end of said container, a galvanometer connected to said thermopile, and retaining means associated with the upper end of said container for holding impregnated cloth

over said open end of said container, whereby heat generated by application of a mustard simulant to said cloth produces an indication on said galvanometer.

WARREN C. JOHNSON.
PHILIP WEHNER.
